UNITED STATES PATENT OFFICE.

JOHN W. ANDERSON, OF LANCASTER, PENNSYLVANIA.

EXTENSION BOW-IRON FOR CARRIAGES.

SPECIFICATION forming part of Letters Patent No. 226,015, dated March 30, 1880.

Application filed September 4, 1879.

To all whom it may concern:

Be it known that I, JOHN W. ANDERSON, of Lancaster, Pennsylvania, have invented a new and useful Improvement in Extension 5 Bow-Irons for Carriages, &c., of which the following is a specification.

My invention relates to improvements in that class of bows or cross-pieces of carriage-poles which are provided with adjustable 10 shackles for connection to the axle-clips of vehicles; and the main objects of my invention are to obtain increased adjustability of the shackles, to so connect them to bars on the bow or cross-piece as to prevent accidents, 15 and to provide the shackles with eyes which will readily accommodate themselves to the clips on the axle.

In the accompanying drawings, Figure 1 is a plan view of the attachment for the bows of 20 carriage-poles; Fig. 2, a front view, partly in section; Figs. 3, 4, and 5, plan views of different parts of the attachment; Fig. 6, a perspective view of part of Fig. 1; Fig. 7, a sectional perspective view of different parts of the 25 attachment separated from but showing their relation to each other; Fig. 8, a vertical section on the line 1 2, Fig. 1; Fig. 9, a perspective view of one of the bolts; and Fig. 10, a general view, drawn to a reduced scale, of part 30 of the pole of a vehicle with bow attached.

The attachment with which each end of the bow is provided is composed of five principal parts—namely, the main bar A, the cover-plate B of the same, the shackle D, the plate 35 E, and bolts F.

The main bar A has opposite vertical flanges a a, between which is fitted the end of the bow G of the pole, the bow extending as far as the cross-piece b of the bar A.

40 The cover-plate B fits snugly to the top of the main bar A, as shown in Fig. 8, and may be secured thereto by any suitable fastenings, set-screws d d, for securing the attachment to the cross-piece G, and a set-screw at e, being 45 used in the present instance for attaching the cover-plate to the main bar.

I prefer to form on the flanges a a of the said main bar lugs c at intervals, and to form notches in the cover-plate for receiving the 50 lugs, so that the proper adjustment of the plate may be assured.

The shackle D is so adapted to a recess in the under side of the main bar that it can be adjusted longitudinally therein, and the slotted portion of the shackle is confined between 55 the bar A and the plate E, which has a recess in the top adapted to the shackle, and which is overlapped by the lower flanges, a' a', of the main bar. The proper lateral position of the shackle in respect to the bar and plate and 60 of the latter in respect to each other is assured by the overlapping flanges a' a' of the main bar.

It will be observed on reference to Fig. 3 that partitions f, f', and f² extend across the 65 longitudinal recess in the top of the main bar. These are for the purpose of strengthening the bar at the point where holes h h pass through both flanges a a for the bolts, which secure the usual diagonal stays shown in the general 70 view, Fig. 10. These partitions are not indispensable; but I prefer them because they serve the additional purpose of counteracting the effect which the slots for receiving the bolts F would otherwise have to weaken the bar.

There are three slots, m, m', and m'', in the main bar, and each slot is enlarged at one point, n, for the free admission of the threaded portions of the stems of the bolts. In like manner and for a like purpose there is an enlargement, p', of the slot p in the shackle, and a similar enlargement, q', of the slot q in the plate E.

It will be observed on reference to Fig. 9 that the bolts F are of peculiar character, the 85 head w being large enough to prevent its passage through any part of either of the slots in the main bar the portion x of the stem nearest the head being flattened and free to slide in the slots, the threaded portion y being larger 90 in diameter than the portion x is thick, and the enlargement of each slot in the main bar being of sufficient size to freely admit the threaded portion of the stem.

Supposing two bolts be used, as in the present case, it will be necessary, in order to fit the several parts of the attachment together and introduce the bolts to their places, to proceed as follows: First, the main bar A, shackle D, and plate E must be so adjusted in respect to 95 each other that the enlargement n of the slot m in the bar, the enlargement p' of the slot p

in the shackle, and the enlargement q' of the slot q in the plate E will coincide with each other, when the stem of one of the bolts is passed through the enlargements, after which 5 the shackle and plate E are moved in the direction of the arrow until the enlarged portions p' and q' of their slots coincide with the enlargement n of the slot m' of the main bar, when the stem of another bolt is passed through 10 these enlargements of the slots, after which the shackle may be adjusted on the main bar to any position which that of the clip on the axle may demand.

The important end attained by this mode 15 of fastening the shackle to the main bar is the prevention of accidents should the nuts of the bolts become loose and detached, in which case, although the parts will be loosened, the shackle cannot be detached, as the bolts are 20 confined in one direction by the head and in the other direction by the shoulder v , Fig. 8, formed on the bolt where the flattened portion of the stem meets the threaded portion.

It will be seen that, as the bolts are movable in the slots, an extended adjustment of 25 the shackle D is obtained.

The inward adjustment of the shackle may be extended by removing the bolt previously 30 in the slot m to the slot m' , this adjustment being sometimes demanded by the position of 35 the clips on a sleigh. In most cases, however, all the adjustment necessary can be obtained by confining the bolts, one to the slot m and the other to the slot m' .

On referring to Fig. 6 it will be seen that 35 the eye M on the shackle for connection to the clip on the axle, instead of forming a rigid part of the shackle, as usual, is hinged horizontally to the same by a pin, N. The importance of 40 this will be understood when it is remembered that the shackle is made adjustable on a curve. No matter what position it may be adjusted to, the eye M will turn on its pin until it is accommodated to the clip.

It may be remarked that the cover-plate B 45 is not an indispensable adjunct to the device

as regards the accomplishment of any other function than that of imparting a proper finish and a neat appearance to the attachment. The plate is intended to be a permanent part of the 50 bar A, and is not removed even when the bolts have to be withdrawn and the shackle detached. When this becomes necessary the bolts may be raised through openings in the plate after a proper adjustment of the shackle 55 and plate E, so that there may be a proper coincidence of the slots, as described above, the openings in the cover-plate being large enough for the free passage of the heads of the bolts, and being closed by screw-plugs u , Fig. 8, 60 which are never detached, excepting for the purpose last described.

I claim as my invention—

1. The combination of the slotted bow A, 65 having at its inner end a socket for receiving one end of the bow of a carriage-pole, the longitudinally-slotted shackle D, the longitudinally-slotted plate E, and bolts for securing the said plates together independently of the wooden bow, all substantially as set forth.

2. The combination of the bar A, shackle D, 70 and plate E with bolts confined vertically, but at liberty to slide in the slots of the said bar, shackle, and plate, substantially as specified.

3. The bar A, shackle D, and plate E, all 75 having slots with enlargements, in combination with bolts F, constructed in respect to the said slots and their enlargements substantially as described.

4. The combination of the bar A, its flanges 80 a , and the bolts with a cover-plate, B, attached to the bar, and having openings through which the bolts can be withdrawn, all substantially as described.

In testimony whereof I have signed my 85 name to this specification in the presence of two subscribing witnesses.

JOHN WESLEY ANDERSON.
